WINDOW LATCH

George A. Houseman, Phoenix, Ariz.

Application February 13, 1947, Serial No. 728,301

5 Claims. (Cl. 292—1)

1.

My invention relates to latches, but more particularly to tamper proof latches for use on screen doors and screen windows.

An object of my invention is to provide a burglar proof, spring actuated, clamping type latch, so constructed that it cannot be operated by means of a wire or like implement pushed through the screen mesh of a door or window on which the latch is mounted.

Another object of my invention is to provide a latch which incorporates a longitudinally extensible arm arranged to work against a spring in order that the latch in the latched position will serve as a means for holding a door or window screen, on which it is mounted, tight up against the door frame or window frame, as the case may be, to prevent the door or window screen from rattling when the wind blows or when vibrated by some other cause.

Other objects and advantages of my invention will appear in the course of my detailed description to follow of a latch and a latch keeper that embodies my invention which I have illustrated in the accompanying drawings in which:

Figure 1 is a side elevational view of a latch and keeper combination embodying my invention, wherein the latch is shown attached to the lower frame member of a window screen fastened to a keeper installed on the window ledge against which the lower edge of the window screen contacts.

Figure 2 is an enlarged cross-sectional plan view of a portion of the latch illustrated in Figure 1.

Figure 3 is an exploded view of parts of the latch.

Figure 4 is an isometric elevational view of the keeper illustrated in Figure 1.

Figure 5 is an elevational view of a portion of the latch and the keeper which illustrates an operation of a latch, and,

Figure 6 is a cross-sectional view of Figure 5 taken on line 6—6 of Figure 5.

In the drawings numeral 10 designates a base plate shown screwed to the lower edge of the frame of the window screen S by means of screws 11. The base plate 10 is provided with an internally threaded socket 12 adapted to receive a spring retaining shell 13 in which is housed a helical compression spring 14. The compression spring 14 urges the plunger 15 to its retracted position shown by the solid lines of Figure 2, a position in which it contacts the base plate 10. The plunger 15, however, may be moved outwardly to an extended position, such as indicated

2.

by its dotted line position of Figure 2, against the force of the spring 14 to enable the latch to make contact with the keeper 28.

The plunger shaft 16 forming an integral part of the plunger 15 is slidably mounted in the shell 13 and terminates in a transversely perforated slotted end 17. By means of a pivot pin 18 the perforated flattened end 20 of the latch arm 19 is pivotably connected to the plunger shaft 16.

Thus, it will be seen that the latch arm 19 may be pulled outwardly and moved up and down to bring the clamp 23 in clamping position on the keeper 28. The clamp 23 is rotatably mounted on the rounded portion 21 which is a right angular extension of the main body portion of the latch arm 19. The upset end 22 of the rounded portion 21 retains the clamp 23 on the rounded portion 21.

The clamp 23 comprises a pair of perforated clamping arms 24 through which the rounded portion 21 of the latch arm 19 is extended. The perforated clamping arms 24 are joined together by means of a C-spring 26. The clamping arms 24 terminate in inwardly curved cooperating clamping jaws 25 adapted to grip the keeper 28. The clamping arms 24 terminate in outwardly curved handles 27 adapted to be gripped by the fingers of the hand in opening the clamping jaws 25 and for pulling the clamp 23 and latch arm 19 assembly outwardly in opposition to the compression spring 14. The keeper 28 is comprised of a base portion 29 which is adapted to be fastened to a window ledge L by means of screws 30 or the like. An upright portion 31 integrally joined to the base portion 29 carrying a pair of parallel rearwardly extending ears 32 is extended upwardly at right angles from the base portion 29. Between the ears 32 a rod 33 is extended. The rod 33 has a diameter less than the diameter of the ears 32. Due to this construction of the keeper the ears 32 serve as stops to prevent the clamp 23 from being slid off the rod 33 by means of a tool inserted through the screen mesh of a window screen or door screen the latch is mounted on.

It is pointed out here that this latch cannot be unfastened from the outside of a window screen or screen door by means of any tool that could be worked through screen mesh. In order to remove the latch from the latch keeper 28 the handles 27 and the clamp 23 must be squeezed together and then the clamp 23, in spread condition, must be pulled back from the rod 33 in opposition to the compression spring 14.

The compression spring 14, by holding the

screen S tightly up against the window ledge L, prevents the screen S from rattling during a windstorm. It is pointed out also that the compression spring 14 and the C spring 26 working together hold all of the movable parts of the latch under spring tension and thus prevent its parts from rattling.

The above described invention in a latch embodying the compression spring 14 and the C spring 26 constitutes a flexible latch, an ideal latch for use on window screens. The clamp 23 is operated in a very simple manner by the thumb and forefinger of the hand. When the clamp 23 is opened and while it is still gripped between the thumb and forefinger of the hand it can be easily pulled backwards into clamping position with the rod 33. No difficulty will arise in fastening the clamp 23 to the rod 33 because of any small angular misalignment of the keeper 28 because the clamp 23 is pivotably mounted on the rounded portion 21 of the latch arm 19 permitting the turning of the clamp 23 into exact alignment with the rod 33. All of these operations, stated above, are carried out simply and naturally by a person using only one hand and without changing his grip on the handles 27.

It is to be understood that various changes in the size and arrangements of parts of the screen latch and the accompanying keeper, illustrated in my drawings and described in my specification, may be resorted to within the scope of my invention. While my specification illustrates my invention in a latch employed on a window screen it is to be understood that its use is not to be limited to window screens, doors, or the like, for it may be used in many other constructions wherein latches are needed.

Having thus described my invention, I claim:

1. A device of the class described, comprising a base member adapted for attachment to a window screen or the like; an elongated latch arm pivotably mounted at one of its ends on said base member, and provided with a spring clamp pivotably mounted on its other end.

2. A device of the class described, comprising

a base member, said base member including a spring retaining shell; a compression spring engaged within said shell under which a plunger, provided with a plunger shaft extending out of said shell is slidably mounted; an elongated latch arm attached at one of its ends to said plunger shaft, said latch arm provided at its other end with a spring clamp pivotally mounted on said latch arm for engaging a latch keeper, or the like.

3. A device as claimed in claim 1, wherein said elongated latch arm terminates in a rounded portion extended in a substantially right angular direction with respect to the major axis of said elongated latch arm, and wherein said spring clamp is rotatably mounted on said rounded portion of said latch arm.

4. A device as claimed in claim 2, wherein said latch arm terminates in a portion extended at a substantial right angle to the major axis of said latch arm, and wherein said means for engaging said latch keeper consists in a spring clamp comprising a pair of complementary curved jaws extending from said right angular portion of said latch arm in a direction toward said base member.

5. A device as claimed in claim 4, wherein said complementary curved jaws are each provided with a rearwardly extending, outwardly curved handle, said handles being opposed to one another and adapted to be squeezed by fingers of the hand in the opening movement of said curved jaws and the sliding movement of said latch arm with respect to said base member.

GEORGE A. HOUSEMAN.
